UNITED STATES PATENT OFFICE.

EDMUND L. MOORE, OF VEGA BAJA, PORTO RICO.

MOTOR ATTACHMENT.

1,239,714.

Specification of Letters Patent. Patented Sept. 11, 1917.

Application filed November 12, 1915. Serial No. 61,192.

To all whom it may concern:

Be it known that I, EDMUND L. MOORE, a citizen of the United States, residing at Vega Baja, Porto Rico, have invented new and useful Improvements in Motor Attachments, of which the following is a specification.

This invention contemplates the provision of an attachment for motor vehicles in the nature of a shield adapted to be arranged within the hood to bridge the hinge or joint between the hood sections, and to overhang the spark plug, to prevent rain or wash water leaking through the hood and wetting the spark plugs and wires connected therewith, resulting in short circuits and trouble in starting the motor.

The nature and advantages of the invention will be better understood from the following description wherein the construction, combination and arrangement of parts are specifically set forth, and clearly defined in the appended claims.

In the drawings forming part of this application like numerals of reference indicate similar parts in the several views and wherein:

Figure 1 is a fragmentary top plan view of the front portion of a machine showing the device forming the subject matter of my invention associated therewith.

Fig. 2 is a transverse sectional view taken on line 2—2 of Fig. 1.

Fig. 3 is a longitudinal sectional view taken on line 3—3 of Fig. 1.

Fig. 4 is a perspective view of one form of support for the shield.

Fig. 5 is a similar view of a modified form.

Fig. 6 is a plan view of the shield.

Referring more particularly to the drawings A indicates generally the front portion of a machine including the radiator B, dash board C and the hood D, the motor being indicated at E. Connecting the radiator B and dash board C is the usual brace rod F, upon which is supported the device forming the subject matter of my invention.

The device is in the nature of an attachment and essentially consists of the brackets 10 adapted to be mounted upon the rod F adjacent the extremities thereof and which support the shield 11. The brackets may be of any suitable formation but as shown in this particular instance consist of oppositely extending supporting arms 12 projecting from the opposite sides of the rod F, and

having their adjacent ends terminating to provide, upstanding attaching members 13 disposed in confronting relation as shown. Each of the members 13 has an oppositely bulged portion 14 for the reception of the rod F about which the members 13 are clamped through the medium of the bolts 15. Secured to the under side of the arms 12 is a shield 11 which preferably consists of a metal plate bolted to the arms by means of the bolts 16, or otherwise suitably secured. While it is stated that the shield consists of a metal plate it is to be understood that the same may be constructed from any other suitable material. As shown the shield is so disposed as to bridge the hinge or joint connection between the hood sections 18 respectively, and is of a width slightly in excess of the width of the motor to prevent any water which might leak through the joint in the hood from dropping upon the spark plug or wires connected therewith, which frequently results in short circuits and causes considerable trouble in starting the machine, it being manifest that should any water leak through the hood it will be directed or guided by the shield 16 to a point at the side of the motor beyond the spark plug with a view of eliminating the above noted objections resulting from the wetting of the spark plug or wires connected therewith.

In the modified form of the invention disclosed in Fig. 5 the bracket 17 is constructed from a single length of suitable material bent upon itself to provide an upstanding intermediate loop 19 which receives the rod F and clamped thereabout by means of the bolt 20 as shown. In other respects the bracket is supported and used in the same manner as described in connection with the preferred form of the invention.

While it is believed that from the foregoing description the nature and advantages of the invention will be apparent without requiring a more extended explanation, it is desired to have it understood that the construction and arrangement of parts herein shown and described is merely illustrative of one embodiment of the invention, and that various changes in this respect may be resorted to when desired as fall within the scope of the appended claims.

What is claimed is:

1. The combination with a motor vehicle including a brace rod connecting the radia-

tor and dash board, and a sectional hood, of a shield arranged within the hood and above the motor and supported by said rod independently of the hood, said shield bridging 5 the joint between the hood sections for the purpose described.

2. The combination with a motor vehicle including a brace rod connecting the radiator and dash board, and a sectional hood, 10 brackets suspended from said rod adjacent the extremities thereof, and a shield carried by said brackets and bridging the joint between the hood sections for the purpose set forth.

3. The combination with a motor vehicle 15 including a brace rod connecting the radiator and dash board, and a sectional hood, of brackets suspended from said rod adjacent the extremities thereof, each of said brackets including oppositely disposed arms projecting from the opposite sides of the rod, and a shield associated with said arms and bridging the joint between said hood sections for the purpose described.

In testimony whereof I affix my signature.

EDMUND L. MOORE
